(57) **CLAIM**

The ornamental design for a digital camera, as shown and described.

DESCRIPTION

FIG. 1 is a front, top and right side perspective view of a digital camera showing our new design;

FIG. 2 is a front, bottom and left side perspective view thereof;

FIG. 3 is a front view thereof;

FIG. 4 is a top plan view thereof;

FIG. 5 is a bottom plan view thereof;

FIG. 6 is a right side view thereof;

FIG. 7 is an enlarged view showing a portion defined by lines 7-7 in FIG. 1; and,

FIG. 8 is an enlarged view showing a portion defined by lines 8-8 in FIG. 2.

The broken lines illustrate portions of the digital camera and form no part of the claimed design.

1 Claim, 8 Drawing Sheets(56)
